UNITED STATES PATENT OFFICE.

SAMUEL F. SNIFFEN, OF NEW YORK, N. Y., ASSIGNOR TO THE MEYER-SNIFFEN COMPANY, (LIMITED,) OF SAME PLACE.

WATER-CLOSET.

SPECIFICATION forming part of Letters Patent No. 319,336, dated June 2, 1885.

Application filed March 18, 1885. (No model.)

To all whom it may concern:

Be it known that I, SAMUEL F. SNIFFEN, of New York city, in the county of New York and State of New York, have invented certain new and useful Improvements in Water-Closets; and I do hereby declare that the following is a full, clear, and exact description thereof, reference being had to the accompanying drawings, making part of this application.

10 My invention relates to a novel structure or improved means by which the usual ventilating tube or flue connected with the upper part of the trap in side-delivery closets can be conveniently coupled to the basin-fixture at either 15 one or the other side of the latter, according as the ventilating tube or flue may happen to be situated relatively to the position which the closet bowl or basin must occupy.

Previous to my invention in that kind of 20 water-closet fixtures in which such ventilating-tubes have been employed it has been suggested to have the porcelain-basin fixture provided at the proper locality with a double or duplex nozzle projecting laterally at each 25 side of the fixture, so that the connection could be made with a ventilating-tube at either one or the other side of the bowl and trap, the nozzle not used for such purpose having to be closed by a stopper or closing device of some 30 suitable description.

I propose to provide for use a fixture in which there shall be but one single nozzle or orifice located at about the usual place, and at the same time render the fixture capable of 35 connection with a ventilating-tube at either one or the other side of the fixture by means of a reversible connection adapted to be placed in either one of two relative positions with the said vent-nozzle, and to be connected to 40 any ordinary ventilating tube or flue at either one or the other side of the closet-fixture.

To this main end and object my invention may be said to consist, first, in the construction 45 of the porcelain part of the water-closet fixture with a vent-opening and bearing-surface adapted to be coupled with a vent-nozzle, which may be applied thereto, so as to project at either one or the other side of the bowl and trap portion of the fixture; and, second, in 50 the combination, with the basin and trap por-

tions of a water-closet thus provided with a single vent-aperture, of a reversible vent-nozzle adapted to be applied to the trap and bowl portions of the closet in either one of two positions for the purposes of ready connection 55 with a ventilating tube or shaft located at either one or the other side of the water-closet, all substantially as will be hereinafter more fully explained.

To enable those skilled in the art to which 60 my invention relates to make and use the same, I will now proceed to describe my invention in that form in which I have so far successfully practiced it, and which is the best now known to me, referring by letters of reference to the accompanying drawings, which form part of this specification, and in which—

Figure 1 is a side view or elevation of a water-closet basin or bowl fixture constructed so as to permit the use in connection with it 70 of a reversible vent-nozzle, such as above alluded to, and which is represented as being composed of the usual porcelain or earthenware, with the bowl portion A, flushing-rim nozzles B, trap C, ascending trunk D, and discharge-leg E, all made integral in about the manner well known to those familiar with the manufacture of the kind of water-closet fixture illustrated. Fig. 2 is a face view of the square flange-like bearing portion, (seen at f, 75 Fig. 1, looking in the direction indicated by the arrow of the last-named figure, and showing more particularly the contour of said part f,) also the vent-aperture g in the upstand portion of the trap C, and the shape and location of each of the notches or cut-outs h, formed in the flange-like portion f of the fixture for the accommodation of the bolts which are used to effect the securement to said part f of the reversible vent-coupling. Fig. 3 is a back 80 view or elevation of the reversible vent-coupling, and Fig. 4 is a side or edge view of the same.

This vent-coupling, as illustrated, is composed of a tubular portion H, which near its 95 root is translated into a flattened tubular form, as seen at I, and has a plate-like or flat square portion, K, which corresponds in size and shape with the bearing-surface of the portion f at the porcelain part of the fixture, the said 100

plate-like portion K being perforated at *i* with preferably round holes for the accommodation of four (more or less) ordinary bolts, by means of which and nuts applied thereto in the usual manner said reversible vent-tube device may be conveniently bolted to the part *f* of the closet-bowl fixture. The plate-like portion K of the reversible vent-tube is of course perforated, so as to permit an open communication between the vent-hole *g* (see Fig. 2) of the trap and the interior of said vent-tube H I, as clearly indicated by the dotted lines at Figs. 3 and 4.

It will be understood that when it is desired to make a connection between the vent-opening *g* and any ventilating tube or shaft located at the right side of the water-closet, the square plate-like portion K of the reversible device shown at Figs. 3 and 4 is applied to the portion *f* of the bowl-fixture in such a position as to have the tubular portion H of the reversible device (seen at Figs. 3 and 4) project at the right-hand side of the closet-fixture, and that where the ventilating tube or shaft happens to be located at the left-hand side of the water-closet said reversible device is applied in an opposite or reversed position.

A suitable gasket or packing-ring, of rubber or other proper material, is of course to be always applied between the bearing or opposing surfaces *f* and K, so as to make a perfectly tight joint between the parts connected together, said parts securely clamping such packing ring or device between them by the action of ordinary bolts provided with suitable nuts, and passing through holes *i* in the reversible vent-coupling and through the cut-out portions or bolt-slots *h* of the portion *f*.

The reversible device seen at Figs. 3 and 4 is made preferably of brass, but may be composed of any suitable material desired; and although I have shown the portions *f* and *K* as being square in contour, these parts, of course, as well as others may be somewhat differently shaped without at all changing the principle of construction or mode of operation of my improved contrivance. I therefore wish to be understood that I do not

limit my claim of invention to any precise details of construction so long as the structure of the basin and trap fixture is such as to permit the coupling thereto of a reversible device adapted also to be connected with any suitable ventilating tube or shaft, and so long as the reversible device illustrated at Figs. 3 and 4 be of proper construction to permit the coupling of such reversible device with the vent-opening *g* in one or another relative position, according to the possible location of the ventilating tube or shaft with which the trap of the water-closet is to be connected.

Having now so fully explained the construction and operation of my invention that any one skilled in the art can make and use the same, what I claim as new, and desire to secure by Letters Patent, is—

1. A porcelain or other cast water-closet bowl or basin fixture formed or provided with an opening at one side of the ascending leg or upstand portion of the trap, as seen at *g*, and with means for the attachment to the fixture at the locality of said opening of a vent-tube coupling arranged to project to either one or the other side of the bowl, as circumstances may require, substantially as hereinbefore set forth.

2. In combination with a water-closet bowl and trap fixture provided with a vent-opening at one side of the ascending leg or upstand portion of the trap, as seen at *g*, and means for coupling with a ventilating device, a reversible vent-tube coupling, substantially such as hereinbefore described, adapted to be coupled with the bowl-fixture in one or another relative position, accordingly as it may be necessary to have said reversible device communicate with a ventilating tube or shaft at one side or the other of the water-closet, as hereinbefore set forth.

In testimony whereof I have hereunto set my hand this 5th day of March, 1885.

SAML. F. SNIFFEN.

In presence of—

F. J. MCRAE,
AMASA T. DAY.
